(57) **CLAIM**

I claim the ornamental design for a remote control vehicle, as shown and described.

DESCRIPTION

FIG. 1 is a front perspective view of a remote control vehicle.

FIG. 2 is a front elevation view of the remote control vehicle of FIG. 1.

FIG. 3 is a rear elevation view of the remote control vehicle of FIG. 1

FIG. 4 is a side elevation view of the right side of the remote control vehicle of FIG. 1.

FIG. 5 is a side elevation view of the left side of the remote control vehicle of FIG. 1.

FIG. 6 is a top plan view of the remote control vehicle of FIG. 1.

FIG. 7 is a bottom plan view of the remote control vehicle of FIG. 1; and,

FIG. 8 is a front perspective view of a remote control vehicle of FIG. 1 shown in a position of use showing the driver ejected from the vehicle.

In the drawings, the broken lines depict portions of the remote control vehicle and its driver that form no part of the claimed design.

1 Claim, 8 Drawing Sheets
